LIGHT SHIELDED HANDLED FIBERBOARD
CASEWillis B. Lincoln, Jr., Indianapolis, Ind., assignor
to Inland Container Corporation, Indianapolis,
Ind., a corporation

Application January 17, 1936, Serial No. 59,559

23 Claims. (Cl. 229—52)

This invention relates to a fiberboard container.

Heretofore in the art, fiberboard containers may have had a divided top with extensions on the free ends thereof which abut in cover-closing position and form what is known as a self-locking arrangement. Also, containers of this character have been provided with interlocking partitions to form cells, each for an individual vessel or article, such as a bottle. Sometimes, two opposite walls are provided with hand openings to permit ready grasping and lifting of the container with the bottles therein.

It is well known there are certain fluids, such as beer, which light affects and causes deterioration and at least one manufacturer of beer has endeavored to avoid such deterioration by bottling it in a colored glass, such as a brown bottle.

The present invention has for one of its chief objects, the adaptation of a container of this general character to the bottle beer industry by providing a light-shield arrangement in juxtaposition to the hand holes or apertures in the container, so that deterioration of the product, due to light exposure, does not occur.

Another chief object of the invention is to reduce the cost of cellular containers by having the opposite ends of each cover-forming portion bear upon a relatively wide bearing portion of the adjacent wall, thus eliminating stacking losses or cover breakage.

One feature of the invention consists in providing a relatively wide bearing near or at the top of a pair of opposite walls which are engaged by the opposite ends of each cover-forming portion and which may, if desired, be interiorly and frictionally engaged by the reduced end portions of the locking extensions carried by the cover-forming portions for additional locking.

Another feature of the invention consists in this relatively wide bearing being juxtaposed relative to the hand hole aperture so that a relatively wide finished gripping surface is available to the fingers for container lifting or transportation.

A further feature of the invention relative to the wide bearing portion is that it serves as an end support for the two ends of each cover-forming portion, thereby permitting the employment of relatively low or shoulder high partitions when desired, although for convenience in the present invention, a median partition of full container height is employed, the latter being notched at its upper end to nestingly receive the cover ex-

tension portions. The latter, however, is unnecessary if extension end contact is provided.

The full height partition has an interlocking and/or operative relationship with the other partitions if of shoulder height so that the latter are retained at the bottom of the container for bottle bottom spacing if accidentally inverted.

Another feature of the invention consists in the reinforced wall structure serving as a relatively wide bearing for superposed containers so that if a stack of containers is not in exact alignment, material deformation of the cover of the next lower container below the non-aligned container will not occur.

Still a further feature of the invention consists in utilizing the material provided by forming the hand hole as a part of the reinforcement encircling arrangement.

The invention is illustrated as embodied in a single blank as well as a multiple blank type container.

The full nature of the invention will be understood from the accompanying drawings and the following description and claims:

In the drawings, Fig. 1 is a top plan view of a container of the general character indicated and embodying the invention, a portion of the cover being open and tilted about 120°.

Fig. 2 is a longitudinal sectional view taken on line 2—2 of Fig. 1 and in the direction of the arrows and illustrates a different embodiment of the invention at each end.

Fig. 3 is an end elevational view, looking at the left-hand end of the container as shown in Figs. 1 and 2.

Fig. 4 is a view similar to Fig. 2 but of a "Bliss" type box structure having a divided top structure.

Fig. 5 is an end elevation thereof similar to Fig. 3 of the container shown in Fig. 4.

Fig. 6 is a perspective view of a Bliss type container with hinged cover and embodying the invention.

Fig. 7 is an enlarged top plan view of a portion of a divided top structure.

In the drawings, 10 indicates a divided bottom, 11 and 12 opposite side walls, 13 and 14 opposite end walls and 15 and 16 end extensions thereof which have overlapping relation with the bottom and reinforce approximately two thirds of the bottom. If desired, these extensions 15 and 16 may substantially abut thus completely reinforcing the bottom.

The respective side and end walls are joined in succession by scored connections and the two

remote edges are suitably secured together to form the outline of the container. For that purpose an extension 17 is provided which herein is carried by one side wall and is nested within one end 5 wall and lies parallel thereto, and the two are secured together by any suitable means, such as the metal stitching or stapling 18 or a taped joint may be used.

Integral with each side wall and having a score 10 type hinge connection, is a cover-forming portion 18 hingedly connected as at 19. In view of the fact that blanks of this character are simultaneously scored and cut, the overall length of the cover-forming portion is slightly less than the 15 overall outside length of the container and thus if the container is of single thickness board formation, the cover portions at opposite ends would not be supported by the end walls.

Each cover portion 18 has hingedly connected 20 to it by the scoring 20, the locking extension 21, the overall length of which is less than the overall length of the cover portion and the ends 22 are inwardly offset the desired amount with reference to the parallel ends of the cover portion 25 for the purpose hereinafter set forth.

Heretofore, it has been the practice in manufacturing containers of the general character described, to provide partitions in spaced relation to each other of the desired number and have 30 each extend from the bottom to the top of the container and thus form a support for the cover.

In the present invention, however, for reasons hereinafter to be set forth, it is not required or necessary that all partitions extend the full height 35 of the container. Herein there are illustrated five partitions, four of them being indicated by the numeral 23, which extend from one side wall to the other and terminate slightly higher than the middle of the container as at 24. The intermediate partition 26 is illustrated as of container depth in height. Three parallel partition members 27 of shoulder height have an interlocking relationship with the partitions 24 and 26. Such interlocking relationship is indicated by the numeral 25. Partition 26 has an interlocking relationship with said members 27 as at 28 and this is the reverse of interlocks 25.

The partition 26 at its midportion and at its upper edge is provided with a notch or recess 29 which is of a width sufficient to accommodate both extensions 21 of the cover-forming portions. With milk bottles, beer bottles, and the like, the partition arrangement disclosed herein is of sufficient separating character and due to the fact 55 that the cover at the ends is otherwise supported, these partitions are not required to extend the full depth of the container for cover support purposes.

In Fig. 2 opposite ends of the container are 60 provided with modified forms of the invention.

Reference will first be had to the left-hand form of the invention. In this form, the end wall 14 is suitably recessed by providing an aperture 30 forming a hand hole or an opening for the reception 65 of the fingers of the hands. The material therefrom is extended laterally as at 31 and thence upwardly as at 32. The upper edge of the end wall 14 has a scored connection 33 with the extension 34 which is lateral thereof, and similarly 70 connected as at 35 is an extension 36 parallel to but spaced interiorly from the end wall 14.

The portions 34 and 36 together with portions 31 and 32 and the included portion of the end wall 14, form a pocket 37 adapted to receive a 75 reinforcing member 38 which is relatively rigid.

This may be in the form of a plurality of single width strips secured together so that the overall thickness and depth of the reinforcing member is that desired, or may be a folded strip of solid fiberboard, corrugated board, wood or metal. 5

Preferably the length of the reinforcing member is that of the length of the end wall 14 so that the member 38 extends from side wall to side wall, thus forming an elongated relatively wide upper bearing at the upper edge of the end wall and interiorly thereof and upon which the free end of the cover portion 18 operatively bears. The portion 36 is extended downwardly and terminates about two thirds of the distance below the top edge of wall 14 and lies parallel thereto and is suitably secured thereto. The interiorly positioned downwardly inclined portion is indicated by the numeral 39, the parallel portion by the numeral 40 and the anchoring staple or clip by the numeral 41. 10 15 20

As illustrated in Fig. 3, the bottom 10 is formed of two portions having the abutting relationship 9 and the same is secured in bottom-forming relation with the portions 15 and 16 by an adhesive or other connection 8. This is the customary form 25 of bottom construction. 25

The single anchorage 41 is sufficient to retain the portions 31 and 32 in encircling relation in association with the other pocket-forming parts relative to reinforcing member 38. Portion 31, of course, is only of the width of the hand opening 30 but it does serve as a bottom retainer for member 38 and furthermore serves as a protector to the fingers should the member 38 be rough or splintered. Member 38 may be of wood, if desired, or of multi-ply paper board or metal as previously set forth. 30 35 40

Reference will now be had to the other form of the invention illustrated in Fig. 2 and more particularly in the right-hand portion thereof. 40 The parts therein identical or similar to the parts shown in the left-hand portion of Fig. 2 bear identical numerals. Thus, the portion 39 serves as a light shield to prevent the entrance of light into the interior of the container when it is covered. 45

Whenever it is desired to permit a more firm grip at the hand hole or aperture, one inclined portion 43, see left-hand portion of Fig. 2, is provided with the substantially U-shaped slitting 50 42 which is in inverted relation and the included portion may be pressed inwardly as at 44, the same having a scored connection 44 with the portion 39. Merely for purposes of illustration, the tilted position of the portion 43 is exaggerated as to its angularity. 55

The top 44 of the cut-out 42 may lie slightly above the lower plane of the portion 31, so that when the portion 43 is slightly tilted inwardly, its upper edge 45 will lie slightly above or approximately in the same plane as the lower surface of the portion 31, thereby insuring a relatively effective light shield. This, however, is not as effective as the form of the invention shown in the right-hand portion of Fig. 2 in which the portion 39 is made unslit and without any tilt-able portion such as 43. 60 65 70

As previously set forth, the relatively stiffened upper end of the end wall prevents bulging of the end wall when the container is lifted with 70 its contents therein and thereby prevents the automatic release or opening of the cover, since the edge 22 of the extension 21 is adapted to frictionally engage the interior exposed surface of the portion 36 of the reinforced enlargement. 75

Figs. 1 and 2 illustrate another feature of the invention which may be necessary whenever semi-high or shoulder high partitions are utilized. This is an interlocking feature which holds the partitions in associated relation adjacent the bottom, even though the container be inverted which frequently occurs when the containers are shipped from the manufacturing plant to the bottling plant. This interlocked relation, as stated, is clearly shown in Fig. 2 and the intermediate partition 26 has an interlocking relationship 28 which is the reverse of the interlocking relationship 25 between partitions 23 and the transversely positioned partitions 27, with which partition 26 also is interlocked.

If desired, the ends 48 and the immediately adjacent portion 39 may be notched to receive the ends of the partitions 27 but in that event, it would probably be necessary to utilize a plurality of staples to secure the portion 40 to the adjacent end wall. Such a notching of the portion 40 and 39 would also serve to hold the shoulder-high partitions in predetermined relationship relative to the bottom of the container.

When the container is filled with bottles and if inverted accidentally, the aforesaid interlocking relationship, whether it be of the last-mentioned character or of the character illustrated or of both characters, prevents the shoulder-high partitions from moving to the neck end of the bottles, permitting the bottom ends of the bottles to contact, thereby insuring against breakage of the bottles, when the case is inverted, by reason of bottom to bottom contact.

This invention in common with structures of this general character, has the advantage that the cover is self-locking and does not require additional sealing to keep the cover closed and it is of such a character that the cover may be repeatedly opened and closed without destruction of the self-locking feature. The reinforcement of the hand engageable portion insures against hand hole deformation in use and that together with the interlocked relationship insures longer life than is ordinarily obtainable in a fiberboard cellular structure of the general character before set forth as old in the art.

The single weight box construction embodying all of these advantages before mentioned, has the additional advantage, not otherwise obtainable in prior art single weight structures, that the entire weight of the container is of the minimum amount, thereby reducing shipping costs and inasmuch as it is made of single weight board and is not generally of a double weight construction, the amount of material required for the container is materially reduced without appreciably reducing its strength or life.

The saving in the use of the reduced or shoulder-high partitions is considerable. This divided top box has all of the advantages of a double wall structure and is of an approximate weight and amount of material of a single wall structure without any of the disadvantages hereinbefore pointed out, which are inherent in single wall prior art containers.

It will also be noted so far as the exterior of the container is concerned, the reinforced top edges of the ends are reinforced interiorly of the container so there is presented an exterior surface of the container which is relatively smooth upon all faces, including side and end walls, top and bottom.

It will also be observed that when the form 75 of the invention shown in the left-hand portion

of Fig. 2 is provided, the fingers may be extended through the opening formed by the cutting 44 and engage the lower edge of the extensions 21 and elevate the same. This eliminates the necessity for providing finger holes in the cover which heretofore have been employed and which have been necessary in order to open the cover. These finger holes admit light to the interior of the container and this form of the invention eliminates the necessity for their presence.

In its broader aspect, the invention contemplates the formation of the ends of either character or both. In other words, the left-hand form of the invention shown in Fig. 2 may be provided at both ends or the right-hand form shown in Fig. 2 may be provided at both ends or both forms of the invention may be provided in a single container. The latter is illustrated herein.

It is to be noted that when the form of the invention shown in the entire Fig. 2 is utilized, the empty container may be fully assembled and then shipped to the bottling plant with the portion 43 in its original position, not as shown in Fig. 2. At the bottling plant, portion 43 is pressed inwardly, the lower edges of the extensions 21 are elevated and then the covers are opened. The member 43 then is pressed outwardly into its original position, the case filled, covers closed and the case is ready for shipment in a relatively light-proof condition—that is, light is not admitted to the interior of the container. Should through accidental contact, or the like, member 43 be slightly tilted from its original position in alignment with portion 39, as before set forth, there is in effect an effective overlapping so that but very little light, if any, will pass into the interior of the container. A container of this character is of the form which may be readily arranged to provide drainage in the event a bottle explodes or is broken. This is because there is an overlapping relationship between the portions 15 and 16 and portions 10 and the two may be so associated together to provide what might be termed, a light-proof drainage arrangement. In other words, the interior portion of the bottom might be grooved so the drainage would run between the two portions of the bottom and then would drain out through appropriate openings covered by the other portion. Herein, the folded arrangement at the corners provides drainage openings 50.

Each divided cover adjacent the hinge score 20 and medianly thereof, is provided with an arcuate slit 51, forming a light shielded finger hole when depressed—see Figs. 1 and 7.

In Figs. 4 and 5 of the drawings, there is illustrated a modified form of the invention. Herein numerals of the 200 series indicate like or similar parts. The chief distinction in the present invention is that the divided cover type container shown in Figs. 1, 3 and 7, instead of being formed from a single blank, is formed from two or three blanks which are arranged in a manner known as a Bliss type container. When formed of two blanks, the sides, bottom and divided top constitute one blank member and the two ends, including the reinforcing arrangement, and a supplemental bottom, constitute the other blank member. When three pieces are utilized, the same first piece is provided and then each end is an individual piece and of a light-shielded and handle reinforced character.

Likewise, in this form of the invention, the light-shielded finger holes for divided top opening are 75

included and as illustrated in Fig. 2, the left-hand light shielded reinforced apertured hole has its light shield yieldingly associated, whereas in the right-hand shield portion, the light shield is 5 non-yieldingly associated therewith.

Since the Bliss type container is well known in the container industry, no detailed description of its specific construction need be set forth. The specific form of Bliss type construction form 10 shown in the present application is of the three-piece type, each end wall being not connected by a supplementary bottom wall. The interlocking between the partitions and end wall, if, as and when desired, may be included as hereinbefore 15 set forth with reference to the form of the invention shown in Figs. 1 to 3 inclusive.

In Fig. 6 there is illustrated in perspective, a similar form of the invention, wherein instead of the Bliss type container embodying a divided 20 top, the same is provided with a single hinge top.

In this form of the invention, numerals of the 300 series indicate similar or like parts. The cover 318 is hingedly connected along one edge to one of the side walls 311 and its other three edges are 25 provided with depending portions 300 suitably secured together at 301, the same constituting a rim on the cover to nestingly receive the upper edges of the other walls. In this form of the invention, the end walls may be of individual character or may be connected together by a secondary bottom and thus the container may be made from two pieces or from three pieces, as desired.

In both forms of the invention illustrated in Figs. 4, 5 and 6, each side wall has extensions 217 35 or 317 which are stapled as at 218a or 318a to the ends 214 or 314, respectively, and each end is provided with a reinforcing structure, such as shown clearly in the upper right and left-hand corners of Figs. 1, 2 and 4, and each end is provided with 40 a light-shielded hand hole or gripping structure, which may be of the character shown in the right-hand portions of Figs. 2 and 4.

The reinforcement of the ends eliminates the 45 possibility of tearing of the end, if the container is grasped at one end while loaded. It also prevents bulging of the end panel.

While the invention has been described as particularly associated with bottled goods, it is not necessarily restricted to the packaging thereof 50 but may be utilized for other articles or materials.

The invention, as will be evident from the foregoing description and the drawings, requires a minimum amount of material, thereby effecting 55 considerable economy. The parts are simple in form and few in number, and the only loose pieces in the container are the partitions when utilized or required and these are so associated together that smaller pieces may be utilized, thereby effecting an additional economy, and they are so 60 associated together that they may be handled as a unit.

While the invention has been described in great detail, the foregoing specification is to be considered as illustrative and not restrictive in character. The modifications illustrated and/or described herein as well as others which will readily suggest themselves to persons skilled in this art, are all considered to be within the broad scope of 65 this invention, reference being had to the appended claims.

It is, of course, to be understood the paper board may be of waterproofed or treated stock and of various types or grades of boards in its broadest phases, and the use of the terminology 70 "paper board" in the claims is intended to cover

all such standard paper boards or paper board stock as are now well known in the industry, such as corrugated, single or double wall board or solid fiber, waxed, lacquered, or otherwise sufficiently treated board.

The invention claimed is:—

1. In a paper board container from a single blank of single thickness board arranged in side and end wall formation with a bottom and a divided top integral with one opposite pair of walls, the combination of an extension on the adjacent free end of each top section, said extensions abutting and forming a self-locking cover, and an integral extension upon each of the other walls and operatively secured to the connecting wall in pocket formation, and a relatively rigid insert in each pocket stiffening the said other walls for the purpose described.

2. In a paper board container having side and end walls, a bottom, and a divided top integral with an opposite pair of walls, the combination of an extension on the adjacent free end of each top section, and of a length less than the length of the top section and terminating short of each end thereof, said extensions abutting and forming a self-locking cover, and a relatively wide interiorly directed bearing portion carried by each of the other opposite walls at the top and interiorly thereof and upon which each top section bears when the cover is closed, the opposite ends of the extensions terminating adjacent the bearing portions.

3. In a paper board container having side and end walls, a bottom, and a divided top integral with an opposite pair of walls, the combination of an extension on the adjacent free end of each top section, and of a length less than the length of the top section and terminating short of each end thereof, said extension abutting and forming a self-locking cover, and a relatively wide interiorly directed bearing portion carried by each of the other opposite walls at the top and interiorly thereof and upon which each top section bears when the cover is closed, the opposite ends of the extensions terminating adjacent the bearing portions and in frictional contact with the inside face thereof.

4. In a paper board container of single thickness board and from a single blank arranged in side and end wall formation with a bottom and a divided top integral with one opposite pair of walls, the combination of an extension on the adjacent free end of each top section, and of a length less than the length of the top section and terminating short of each end thereof, said extensions abutting and forming a self-locking cover, and an integral extension upon each of the other walls and operatively secured to the connecting wall in pocket formation and upon the interior of the wall and at the top thereof and substantially co-extensive with the top edge to form a relatively wide interiorly directed bearing portion and upon which each top section bears when the cover is closed, and a relatively rigid insert in each pocket for stiffening the single width wall to prevent wall buckling and cover opening, the ends of the top extension terminating adjacent the bearing portions.

5. In a paper board container of single thickness board and from a single blank arranged in side and end wall formation with a bottom and a divided top integral with one opposite pair of walls, the combination of an extension on the adjacent free end of each top section, and of a

length less than the length of the top section and terminating short of each end thereof, said extensions abutting and forming a self-locking cover, and an integral extension upon each of the other walls and operatively secured to the connecting wall in pocket formation and upon the interior of the wall and at the top thereof and substantially coextensive with the top edge to form a relatively wide interiorly directed bearing portion and upon which each top section bears when the cover is closed, a relatively rigid insert in each pocket for stiffening the single width wall to prevent wall buckling and cover opening, the ends of the top extension terminating adjacent the bearing portions, each reinforced wall having a hand aperture therein in juxtaposition to the reinforcement, and a light shield immediately adjacent said aperture for the purpose set forth.

6. In a paper board container having side and end walls, a bottom, and a divided top integral with an opposite pair of walls, the combination of an extension on the adjacent free end of each top section, and of a length less than the length of the top section and terminating short of each end thereof, said extensions abutting and forming a self-locking cover, a relatively wide interiorly directed bearing portion carried by each of the other opposite walls at the top and interiorly thereof and upon which each top section bears when the cover is closed, the opposite ends of the extensions terminating adjacent the bearing portions, one pair of opposite walls each having an aperture therein for hand insertion, and a light shield for the aperture for the purpose described.

7. In a paper board container of single thickness board and from a single blank arranged in side and end wall formation with a bottom and a divided top integral with one opposite pair of walls, the combination of an extension on the adjacent free end of each top section and of a length less than the length of the top section and terminating short of each end thereof, said extensions abutting and forming a self-locking cover, and an integral extension upon each of the other walls and operatively secured to the connecting wall in pocket formation and upon the interior of the wall and at the top thereof and substantially co-extensive with the top edge to form a relatively wide interiorly directed bearing portion and upon which each top section bears when the cover is closed, a relatively rigid insert in each pocket for stiffening the single width wall to prevent wall buckling and cover opening, the ends of the top extension terminating adjacent the bearing portions, each pocketed wall having an aperture therein for hand insertion, and a light shield for the aperture for the purpose described.

8. In a fiberboard container having side and end walls, a bottom, and a divided top integral with an opposite pair of walls, the combination of an extension on the adjacent free end of each top section, and of a length less than the length of the top section and terminating short of each end thereof, said extensions abutting and forming a self-locking cover, a relatively wide interiorly directed bearing portion carried by each of the other opposite walls at the top and interiorly thereof and upon which each top section bears when the cover is closed, the opposite ends of the extensions terminating adjacent the bearing portions, a second-mentioned pair of opposite walls each having an aperture therein for

hand insertion, and a light shield for the aperture for the purpose described, the cover extensions having frictional contact with the interior of the adjacent second-mentioned pair of walls.

9. In a paper board container, the combination of a wall having an aperture therein for hand insertion, a reinforcing structure immediately adjacent thereto and above the same, and a light shield for the aperture for the purpose described, said reinforcing structure including an integral extension of said wall extending angularly and parallel to said wall and forming a pocket, and an insert in said pocket, 5 10

10. In a paper board container, the combination of a wall having an aperture therein for hand insertion, a reinforcing structure immediately adjacent thereto and above the same, and a light shield for the aperture for the purpose described, said reinforcing structure including an integral extension of said wall extending angularly and parallel to said wall and forming a pocket, and an insert in said pocket, 15 20

20. 11. In a paper board container, the combination of a wall having an aperture therein for hand insertion, a reinforcing structure immediately adjacent thereto and above the same, and a light shield for the aperture for the purpose described, said reinforcing structure including an integral extension of said wall extending angularly and parallel to said wall and forming a pocket, and an insert in said pocket, 25 30

30. 12. In a paper board container, the combination of a wall having an aperture therein for hand insertion, a reinforcing structure immediately adjacent thereto and above the same, and a light shield for the aperture for the purpose described, said reinforcing structure including an integral extension of said wall extending angularly and parallel to said wall and forming a pocket, and an insert in said pocket, 40 45

45. 13. In a paper board container, the combination of a wall having an aperture therein for hand insertion, a reinforcing structure immediately adjacent thereto and above the same, and a light shield for the aperture for the purpose described, said reinforcing structure including an integral extension of said wall extending angularly and parallel to said wall and forming a pocket, and an insert in said pocket, 50 55

55. 14. In a paper board container, the combination of a wall having an aperture therein for hand insertion, a reinforcing structure immediately adjacent thereto and above the same, and a light shield for the aperture for the purpose described, said reinforcing structure including an integral extension of said wall extending angularly and parallel to said wall and forming a pocket, and an insert in said pocket, 60 65

70. 75

- in alignment with the aperture and comprising said light shield.
15. In a paper board container having at least a bottom and two opposite walls directed upwardly therefrom, the combination of extension means connected to each of said walls and extending laterally of the upper portion thereof and thence substantially parallel thereto to form a pocket, a relatively rigid elongated insert in each pocket, and means operatively associated with the wall and extension means and secured thereto to retain the insert in the pocket.
16. A container as defined by claim 15, characterized by the end wall including a hand hole aperture positioned below the insert.
17. A container as defined by claim 15, characterized by the end wall including a hand hole aperture positioned below the insert, and the portion removed to form the said aperture constituting the last-mentioned means.
18. In a paper board container having at least a bottom and two opposite walls directed upwardly therefrom, the combination of an extension integral with the top of each wall and extending laterally thereof and thence downwardly to form a pocket and thence reversely toward the wall, a relatively thick and rigid, elongated insert in the pocket, the wall being apertured immediately below the insert for hand hole purposes, and means connected to the wall
- above the aperture and extending laterally below the insert and upwardly adjacent thereto for insert retention in the pocket.
19. A container as defined by claim 18, characterized by the last-mentioned means being formed from the wall and providing the aperture therein.
20. A container as defined by claim 18, characterized by the initial extension extending inwardly of the container and the insert being positioned within the container.
21. A container as defined by claim 18, characterized by the initial extension extending inwardly of the container and the insert being positioned within the container, and by the last-mentioned means being formed from the wall and providing the aperture therein.
22. A container as defined by claim 18, characterized by the reversely and wall-directed portion of the extension having wall contact and by the addition of means securing the portion to the wall.
23. A container as defined by claim 18, characterized by the reversely and wall-directed portion of the extension having wall contact and terminating appreciably below the hand hole and above the bottom, and by the addition of means securing the portion to the wall.

WILLIS B. LINCOLN, JR. 30

DISCLAIMER

2,078,087.—*Willis B. Lincoln, Jr.*, Indianapolis, Ind. **LIGHT SHIELDED HANDLED FIBER BOARD CASE.** Patent dated April 20, 1937. Disclaimer filed July 3, 1939, by the assignee, *Inland Container Corporation*.
Hereby enters this disclaimer to claims 2, 3, 6, and 8 to 14 inclusive of the specification.

[*Official Gazette August 1, 1939.*]

- in alignment with the aperture and comprising said light shield.
15. In a paper board container having at least a bottom and two opposite walls directed upwardly therefrom, the combination of extension means connected to each of said walls and extending laterally of the upper portion thereof and thence substantially parallel thereto to form a pocket, a relatively rigid elongated insert in each pocket, and means operatively associated with the wall and extension means and secured thereto to retain the insert in the pocket.
16. A container as defined by claim 15, characterized by the end wall including a hand hole aperture positioned below the insert.
17. A container as defined by claim 15, characterized by the end wall including a hand hole aperture positioned below the insert, and the portion removed to form the said aperture constituting the last-mentioned means.
18. In a paper board container having at least a bottom and two opposite walls directed upwardly therefrom, the combination of an extension integral with the top of each wall and extending laterally thereof and thence downwardly to form a pocket and thence reversely toward the wall, a relatively thick and rigid, elongated insert in the pocket, the wall being apertured immediately below the insert for hand hole purposes, and means connected to the wall
- above the aperture and extending laterally below the insert and upwardly adjacent thereto for insert retention in the pocket.
19. A container as defined by claim 18, characterized by the last-mentioned means being formed from the wall and providing the aperture therein.
20. A container as defined by claim 18, characterized by the initial extension extending inwardly of the container and the insert being positioned within the container.
21. A container as defined by claim 18, characterized by the initial extension extending inwardly of the container and the insert being positioned within the container, and by the last-mentioned means being formed from the wall and providing the aperture therein.
22. A container as defined by claim 18, characterized by the reversely and wall-directed portion of the extension having wall contact and by the addition of means securing the portion to the wall.
23. A container as defined by claim 18, characterized by the reversely and wall-directed portion of the extension having wall contact and terminating appreciably below the hand hole and above the bottom, and by the addition of means securing the portion to the wall.
